UNITED STATES PATENT OFFICE.

LEON M. HARWOOD, OF SPRINGFIELD, MASSACHUSETTS.

MACHINE FOR CUTTING, PACKAGING, AND UNWINDING METALLIC LEAF.

1,155,727.

Specification of Letters Patent.

Patented Oct. 5, 1915.

Application filed January 26, 1915. Serial No. 4,552.

To all whom it may concern:

Be it known that I, LEON MARTIN HARWOOD, a citizen of the United States of America, residing in Springfield, county of Hampden, and State of Massachusetts, have invented certain new and useful Improvements in Machines for Cutting, Packaging, and Unwinding Metallic Leaf, of which the following is a specification.

10 This invention relates to improvements in machines for cutting, packaging, and unwinding metallic leaf.

In the manufacture of package rolls of metallic leaf, heretofore, a preliminary roll has first been formed by winding the lapped sheets of metallic leaf upon a cylindrical core of wood or other suitable substance, together with the required supporting strip of paper and then dividing the preliminary 20 roll, thus formed, into package rolls of the desired widths. There are objections to these styles of rolls. First,—the extra time required and the loss of gold in lapping for a continuous strip. Second,—in the cutting 25 of the preliminary roll to the smaller widths, there is a loss of gold, and trouble is experienced in loosening of the cores contained by them. Third,—when there are so many widths required, it necessitates a user to 30 carry a large stock of the various widths, and time is required to make the necessary adjustments.

In my device, the leaf need not be lapped in a continuous manner, but is spaced on the 35 supporting strip; the preliminary roll need not be divided into smaller rolls of the smaller widths as in this device the leaf is divided into the required widths by cutting the full width roll in the process of unwinding. The device is applicable, however, to any size or width of commercial roll of lapped metallic leaves. Further, in the 40 packaging of metallic leaf in the roll form, heretofore, the beaten leaf has first been cut 45 or trimmed on a cutting cushion, then the leaf has been placed directly on a conveyer table of a packaging roll gold machine; or the leaf has been taken from the cushion, packed in book form, and then placed on the 50 conveyer or table of the packaging machine. By this device, the conveyer or table of the packaging machine serves also as the

cutting place for the beaten leaf, and the original cutting table may be dispensed with.

55

Referring to the drawings—Figure 1 is a side elevational view showing the two supporting drums, the endless conveyer supported by these drums, a roll of the supporting strip on which the metallic leaf is wound, together with the suction box, pressure wheel, and leaf-cutting knives; Fig. 2 is a transverse sectional view on the line 2—2 of Fig. 1 showing the relative location of the supporting strips, pressure wheels, 65 the cutting knives, and suction box; and Fig. 3 is an enlarged detail view of one end of the suction box and one of the cutters passing through the gold leaf and its supporting strip and engaging the endless 70 perforated conveyer.

Referring to the drawings in detail, 1 is a platform or supporting base member on which are placed the uprights 2 and 3 for rotatably supporting the drums 4 and 5 on 75 the bearings 6 and 7. The drum 4 is adapted to be actuated by means of the handle 8. Passing around these drums is an endless perforated conveyer 9 which is composed of some material that will not dull the cutters 80 and one that can be readily perforated, as very thin sheet zinc, for example. Located between the drums and the framework 10 is a suction box 11.

12 designates an upright in which the roll 85 of supporting strip for the gold leaf is rotatably mounted, as indicated at 13. This upright is formed with an elongated slot 14 in order to readily permit the shaft 15 to rise and fall as the roll unwinds. 16 designates an elongated slot at the upper end of this standard 12 to receive the pivot 17 of the weight 18. This weight is for the purpose of preventing the supporting strip from feeding too fast as it is drawn from 90 the roll, as will be described in the operation of the machine.

19 are pressure wheels which come into contact with the outer edge 20' only of the paper supporting strip which is indicated at 100 20, the gold leaf being indicated at 21, most clearly in Fig. 3.

Attached to the side of the suction box 11 are bracket arms 22 which rotatably support

the cutter shaft 23 on which the thin disk cutters 24 are mounted. These cutters are designed to be laterally moved on the shaft 23 by loosening the set screws 25.

26 designates a suitable suction device for exhausting the air from the suction chamber 11, the suction device being connected thereto by means of a pipe 27.

The operation of my device may be described as follows: Considering the drum 4 to be rotated by the handle 8, the supporting strip 20 will be held to the perforated conveyer 9 by means of the suction box 11 which, in turn, will cause the gold leaf 21 to 15 adhere tightly to the supporting strip. As the handle 8 is rotated carrying the strip along with it, the cutters 24 will engage the leaf 21 and sever the same into strips as long as the handle 8 is rotated. The supporting strip is kept tight by means of the pressure rollers 19 and the weight 18 on the preliminary or package roll 13. It will be noticed, from Fig. 2, that the pressure rolls 19 engage only the opposite edges 20' of the supporting strip 20. The position of the cutters 24 on the shaft 23 determines, of course, the width of the leaf that is to be cut. After the leaf is cut the user can readily pick up the severed strip of metallic leaf and apply 30 it to whatever object he wishes. It is to be understood that the user can sever the strips transversely or longitudinally by any suitable cutting means on the conveyer.

It may be stated that this device is reversible, that is to say, it may be used for forming the package roll 13 as well as for unwinding the same. This can be readily accomplished by rotating the shaft 15 by any suitable means as by placing a crank 15² 35 on the squared end 15' of the shaft 15, causing the supporting strip 20 and the leaf in contact therewith to be wound on to the core 28, the suction box serving to cause the leaf to adhere to the conveyer where it can be 40 cut, the pressure wheels 19 being then made to extend across the machine, as shown by the dotted line 19' or, in other words, as a single roller. In using the machine, the suction box can be made longer and, in making 45 the packaging roll, the supporting strip comes into contact with the metal leaf prior to passing under the roller 19'.

It is also to be understood that the endless conveyer 9 may be electrified by means of 50 a suitable friction device indicated at 9', whereby the metallic leaf and supporting strip will be attracted and adhere to the conveyer.

It is to be understood that when the term 55 "table" is used herein that it refers to the endless conveyer or other device upon which the leaf and supporting strip are placed.

It will be seen from this construction that I have produced a device that readily per-

mits the user of the gold leaf to cut strips 65 of the same in any desired width or size, which can be used to advantage for the unwinding or the packaging of metallic leaf.

It will be observed from Fig. 3 that the cutting knife or disk 24 is located between 70 the perforations in the conveyer 9, the pressure rollers 19 serving, as stated, to exert a lateral tension for the purpose of maintaining the supporting strip in a stretched condition during the cutting process. 75

What I claim is—

1. In a device to cut roll metallic leaf, an endless conveyer upon which the metallic leaf and supporting strip are unwound, means to attract or hold the leaf and supporting strip to the conveyer, means to cut the leaf upon the conveyer. 80

2. In a device to cut metallic leaf, a cutting table, means to unwind spaced or single leaves of roll metallic leaf upon the 85 table, means to attract or hold the leaf to the table, and means to cut the leaf on the table.

3. In a device to cut roll metallic leaf, a cutting table, means to unwind the leaf 90 upon the table, means to attract or hold the leaf to the table, means to cut the leaf on the table.

4. In a device to cut metallic leaf, the combination of an endless conveyer, means 95 to cause the leaf to travel therewith, a core rotatably supported upon which the metallic leaf and supporting strip may be wound, means to rotate the core with the movement of the conveyer, means to attract the leaf to the conveyer, means to cut the leaf on the conveyer. 100

5. In a device to cut metallic leaf as desired, the combination of a cutting table upon which the metallic leaf is placed, a rotatably supported core upon which the metallic leaf and supporting strip may be wound, means to rotate the core with the movement of the table, means to attract the leaf to the table, means to cut the leaf on 110 the table. 105

6. In a device to cut metallic leaf, a perforated table upon which the metallic leaf is placed, suction means connected to the table, whereby the leaf is held to the table, so that the same may be cut. 115

7. In a machine of the class described, the combination, of a base member, rotatable drums mounted thereon, an endless perforated conveyer passing over the drums, a suction device located relative to the conveyer, means to operate the drums, means to support a package roll relative to the conveyer, a tension device for the package strip and metallic leaf, and cutters located 120 in operative relation to the leaf, whereby a strip of metallic leaf may be severed when the drums are operated. 125

8. A machine to cut metallic leaf, comprising, in combination with a cutting surface upon which the leaf to be cut is placed, a supporting strip, means to attract the leaf on said surface, means to impart movement to said surface to carry the strip and leaf along therewith, and cutting means to engage the leaf when the same is moved, as described.
